UNITED STATES PATENT OFFICE

CLIFFORD REGINALD LE GRICE, OF NEW LYNN, AUCKLAND, NEW ZEALAND

FLUSHING APPARATUS

Application filed December 27, 1929, Serial No. 416,957, and in New Zealand March 18, 1929.

This invention relates to flushing valves for the purpose of delivering a desired quantity of water from a cistern for flushing sanitary devices, such as water closets and the like, and particularly to the kind in which a piston is slideable in a cylinder and controlling a valve between the cylinder and the flushing pipe.

The object of the present invention is to simplify the construction of such devices and to render them at the same time silent and reliable.

According hereto the device consists of a cylinder attached to a tank or cistern and having openings for water to flow from the cistern into the cylinder, the openings below the piston being considerably greater than the opening above the piston. A piston is slideable in the cylinder and carries a valve 20 for closing an outlet from the cylinder into the flushing pipe. A channel or by-pass of greater area than the area of the opening into the space above the piston, leads from the cylinder at a position above the piston and 25 passes through a releasing valve located on the exterior of the cistern and thence into the flushing pipe at a position below the valve. The release valve normally closes the by-pass but, upon being operated, opens the passage 30 through the by-pass thereby releasing the water in the space above the piston, and the pressure below the piston will raise it and allow the water in the tank to pass through the opening and into the flushing pipe. As 35 soon as the water is emptied from the tank, air leaking into the space above the piston permits the valve to slowly fall and silently close upon its seat, permitting the tank again to fill.

The invention will be described with the aid of the accompanying drawings, wherein:

Figure 1, is a view showing the device in a flushing tank.

Figure 2, is a cross section through the device showing the valve in its normal closed position.

Figure 3, is a cross section through the device showing the valve in its open position 50 with the piston in cross section.

Figure 4, is a cross sectional plan on line A—A Figure 3.

Figure 5, is a cross section through the release valve.

Referring to the drawings, the device is 55 there shown with its cylinder 1 attached to the bottom of a tank 2 by being threaded therein and secured by a nut 3 (see Figure 1), this tank being closed and having an inlet pipe 5 from a source of supply at a higher 60 level so that the required pressure is given within the tank, as for example, this inlet may be direct from a high pressure water supply. The cylinder wall has openings 4 to enable the water from the tank to flow 65 therein, while a valve seating 6 extends around an outlet 7 in the bottom of the cylinder. A piston 8 is slideable in the cylinder and carries a valve 9 by means of its stem 10 which is guided in a cover of the cylinder 70 freely enough to permit air to slowly leak into or out of the cylinder past the stem. The valve is adapted to seat upon the seating 6, thereby closing the outlet 7 from the cylinder 75 1 into the part 11 from which leads the flushing pipe 24. The area of the outlet 7 is greater than that of the inlet 5 so that the tank may empty by means of such outlet while the water is still entering by the inlet. An aperture 12 above the normal position of 80 the piston enables water in the tank to pass into the space above the piston so as to establish equilibrium on both sides thereof, while a by-pass 13 leads from this space downwards 85 in the wall of the device, the cross sectional area of this by-pass being greater than that of the aperture 12. From the by-pass 13 which leads outside the tank, a pipe 14 leads to a passage 15 in a release valve casing 16 (see Figure 5), and having a valve seating 90 17 from which leads a passage 18 to which is connected another pipe 19 carried into the flushing pipe 24 as shown in Figure 1. A valve 20 having a stem 21 is normally retained on its seat by a spring 22 in compression between the neck of the casing and a button 23 thereby closing the passage 15 from the passage 18. This release valve may be attached in any convenient position, either 95 close to the tank 2 or a considerable distance 100

from it, the drawing (Figure 1) showing it attached to the flushing pipe by means of a band 26.

- The tank 2 will fill from the pipe 5 until 5 the air therein is compressed to the pressure according to that of the head of water supplying the tank by the pipe 5, filling the cylinder on each side of the piston by flowing through the openings 4 and the aperture 12, 10 air from above the cylinder leaking past the valve stem, and as the pressure increases the valves 8 and 20 will be tightened on their seatings thus preventing exit of water from the tank.
- 15 To operate the device for flushing purposes, the button 23 of the release valve is pushed causing the valve 20 to open, thus making communication between the space above the piston and the interior of the flushing pipe 11 and permitting water in the said space to flow through the by-pass, and since the by-pass is greater in area than the aperture 12, the pressure above the piston is released. Immediately this occurs, the water 20 beneath the piston having greater pressure thereon than upon the surface of the valve owing to the greater area of the piston, will raise the piston thereby shutting off further entrance of water through the aperture 12.
- 25 The water in the tank now passes through the opening 7, being enabled to pass out by the expansion of the air compressed within the tank, the flow continuing until pressure of the water no longer overcomes the weight 30 of the valve and piston. The water level, being now below the top of the cylinder, air will leak into the space above the piston, past the stem 10, permitting the valve to fall slowly and to close silently upon its seating. The 35 outlet 7 being closed, the tank will again fill 40 as above explained.

What I claim is:—

1. A flushing apparatus comprising a closed cistern, a cylinder extending into the 45 cistern, a cover for the cylinder having a central opening, a flushing pipe leading downwardly upon the cylinder, a valve seat between the cylinder and flushing pipe, a valve normally closing the seat, a piston freely 50 slidable in the cylinder and of greater area than the valve, said cylinder having openings therein below the piston, said cylinder having an aperture in its wall above the piston adapted to be closed by the piston when 55 the same rises in the cylinder, said aperture being of less area than the openings, the cylinder having a by-pass in its wall and opening at one end above the piston and discharging at a point below the valve seat, the area of 60 the by-pass being of greater capacity than the area of the aperture, a stem connecting the valve and piston and projecting from the valve, said stem being guided in the opening of the cover and freely fitting in said opening 65 whereby air may leak past said stem, and a

release valve normally closing the by-pass, and adapted when open to permit water to flow from the cylinder above the piston into the flushing pipe, as and for the purpose set forth.

2. A flushing apparatus comprising a cistern, a cylinder extending into the cistern, a piston slideable in the cylinder, said cylinder having openings in its wall and its lower end, said cylinder having an aperture intermediate its ends, a valve seat in the bottom of the cylinder, a valve cooperative with the seat, a stem connecting the valve and piston and having a part freely slideable in the top of the cylinder, a flushing pipe leading from the cylinder, said cylinder having a by-pass in its wall, a casing supported by the flushing pipe, a normally seated valve in the casing, and pipes connecting the flushing pipe and casing upon opposite sides of the latter valve as and for the purpose set forth.

In testimony whereof, I have signed my name to this specification.
